UNITED STATES PATENT OFFICE.

JOSEPH LOUIS ADHEMAR BOREL AND EMILIE GRANGE, NÉE BOREL, OF ANNECY,
FRANCE.

MACHINE FOR INSERTING RETAINING-SPRINGS IN CAP-LIKE MEMBERS OF PRESS-
BUTTONS OR THE LIKE.

1,317,682.

Specification of Letters Patent.

Patented Oct. 7, 1919.

Application filed October 30, 1917. Serial No. 199,318.

To all whom it may concern:

Be it known that we, JOSEPH LOUIS ADHEMAR BOREL and EMILIE GRANGE, *née* BOREL, citizens of the Republic of France, residing 5 at 2 Rue Notre Dame, Annecy, Haute Savoie, in the Republic of France, have invented certain new and useful Improvements in Machines for Inserting Retaining-Springs in Cap-Like Members of Press-Buttons or the like, of which the following is a specification.

The present invention relates to a machine for the purpose of engaging the retaining springs in the cap like member of press buttons, and of forcing the edges of the said 15 cap like members down on to the springs.

This machine is characterized by the combination and arrangement of its various constituent parts, comprising in particular:—

20 1. A positioning tool for the purpose of engaging the spring in the cap like member of the press button;

25 2. A tool that serves to force the edges of the cap like member over the retaining spring;

30 3. A pusher for the purpose of disengaging the spring from the positioning tool so as to make it enter the cap like member of the press button;

35 4. A thrust member that receives the cap like member of the press button, the said thrust member being pierced by a passage through which air may be drawn out or injected for the purpose of holding fast or throwing out the cap like member;

5. An air-distributing valve.

This machine permits of the rapid manufacture of press buttons, and insures the perfect formation thereof.

40 By way of example, this invention will be described with reference to the accompanying drawing, in which:—

Figure 1 shows a plan of the machine as a whole.

45 Fig. 2 is a sectional elevation of the positioning device, the parts thereof not in operation.

Fig. 2^a is a sectional elevation of the thrust device, not in operation.

50 Fig. 3 is a sectional elevation showing the parts of the machine at the moment when the spring is being put into its place.

Fig. 4 is a sectional elevation showing the position of the parts of the machine at

the moment when the edges of the cap like member are being turned over the retaining spring.

Fig. 5 is a cross sectional view along the line A—A of Fig. 2.

Fig. 6 is an end view of the thrust member, with the cap like member of the press button and the spring.

Fig. 7 shows the air-distributing valve separately in section.

Fig. 8 shows the spring and cap like member prior to their insertion in the machine.

As may be seen from this drawing, the machine comprises a slide guide *a* provided with a positioning tool *b*, the object of which is to insert the spring *c* in the cap like member *d*, and with the tool *e*, which serves to turn the edges of the cap like member over the spring, these various parts being carried by a sleeve *f*.

The member *b* constituting the positioning tool that serves to insert the retaining springs *c* in the press buttons consists of a blade having a projecting stop *b'*, a slightly narrowed part *b*² and a notch *b*³. This blade is normally held in the position shown in Fig. 2 by a spring *g*. It is on this blade that the spring *c* to be inserted is placed.

Surrounding the blade of the positioning tool *b* there is a slidable sleeve *h* for the purpose of disengaging the retaining spring *c* from the blade *b* in order to press it into the cap like member *d*. This sleeve *h* is provided internally with a stop *h'* adapted to cooperate with a stop or projection *b*⁴ on the blade *b*.

Surrounding the sleeve *h* there is a coil spring *i*. Finally, surrounding the blade *b* and the sleeve *h* there is the closing or flanging tool *e*, provided with a groove *e'* for the purpose of turning the edge of the cap like member *d* over the spring *c*.

The closing or flanging tool *e* is rigidly secured to the sleeve *f*. Both the positioning tool *b* and the sleeve *h* are adapted to slide within the tool *e*, which, as shown, is made hollow, for the purpose of accommodating these parts.

The various members of the machine are arranged on the table *j* as shown in Fig. 1 of the drawing.

Facing the tool *b* is a frame *k*. In this frame is slidably mounted a thrust member *l*, the rear part of which is supported in a

guide m , one end of which forms an abutment m' .

The member l receives the cap-like member d on its free end, and it is pierced with 5 a passage l' through which air is drawn out or injected for the purpose of holding fast or throwing out the cap-like member d . For this purpose a pipe n connects the passage l' with the casing u' of a suitable distributing valve (Fig. 7).

The free end of member l is engaged in a sleeve o which is pressed against the frame k by a spring p .

The thrust member l is held back when 15 necessary by a catch q , which co-operates with a notch q' from which it is disengaged at the proper time by a cam r through the intermediary of a lever y pivoted at y' and connected with catch q through a pivoted link y^2 . As shown in Fig. 2^a catch q is provided with a slot q^2 through which passes a small screw q^3 whereby the catch is guided in a vertical direction.

After the disengagement of the catch q 25 the member l is carried backward by the bell-crank lever s , pivoted at t .

The distributing valve u comprises a cylinder u' , a slide-valve piston u^2 , a vacuum pipe u^3 , a pressure pipe u^4 , and an opening 30 u^5 in the piston. The opening u^5 registers alternately with the pipe u^3 and the pipe u^4 , the piston obturating the other pipe.

The machine also comprises: a driving pulley 1, a shaft 2, a cam 3 acting on the 35 slide guide a , bevel pinions 4, a shaft 5, a cam 6 acting on the frame k through the medium of the slide guide k' , bevel pinions 7 driving the shaft 8 which carries the cams r and v . The shaft 5 likewise carries 40 the valve cam 9 that operates the slide-valve piston u^2 . Suitable means such as springs 10 and 11 may be provided for returning the carriages a and k' , respectively, to their 45 inactive positions.

We will now describe the operation of the machine.

A spring c being placed on the blade b , and the cap-like member d of a press button being presented in front of the thrust member l , the left-hand end of which is 50 then flush with the ring o , if at this moment the cap-like member d is pressed on to the member l the latter will be pushed back until the catch q holds it in the position it 55 occupies as shown in Fig. 2^a of the drawing.

At this moment a vacuum is produced in the passage l' of the thrust member, which causes the cap-like member d to be held thereto.

60 During this time the slide guide a moves toward the right and approaches the frame k , carrying with it as a whole the positioning device contained in the sleeve f . As a result of this movement of the slide guide 65 the narrow part b^2 is pressed against the

bottom of the cap-like member d , in such a way that the nipple d' of the latter becomes lodged in the notch b^3 ; but since the spring s' controlling the thrust member l is stronger than the spring g controlling 70 the tool b , the latter stops in its movement toward the right and compresses the spring g ; furthermore, the remainder of the unit continuing to move in the same direction, the sleeve h slides over the blade b and 75 comes into contact with the spring c , which it drives toward the nipple d' . On contact with the nipple d' the branches open out, subsequently closing again in the recesses or 80 openings d^2 formed in the nipple d' near its junction with the cap-like member d .

During the introduction of the spring c into the cap-like member d , the spring i pushes the sleeve h forward. The movement of the slide guide a still continuing in 85 the same direction, the projection or stop b^4 on the blade b comes into contact with the stop h' on the sleeve h ; but since the spring i is more powerful than the spring g , the tool b and the sleeve h move 90 in unison toward the right. Under the combined action of these parts the thrust member l also moves in the same direction, the cap-like member d being carried along with it, while, owing to the pressure exerted 95 from both sides on the spring c , its legs c' are caused to close and to enter the sleeve o , Fig. 3. The thrust member l continues its movement toward the right until it comes into contact with m' . The sleeve h being 100 then stopped by the member l compresses the spring i and sinks into the flanging or closing tool e , while the latter, pressing against the sleeve o , Fig. 4, pushes the latter back while compressing the spring p . As 105 shown in Fig. 4, the groove e' in the flanging or closing tool e then engages the peripheral edge of the cap-like member d , the inner wall of the groove co-operating with the sleeve h to force the branches c' of the spring c into 110 the cap-like member d , while the outer wall of the groove turns the edge of the member d over the spring c which is thus firmly secured in position.

When the operation of engaging the 115 spring in the cap-like member and turning the edges of the latter down on to it is completed, the slide guide a returns toward the left under the action of spring 10 and all the parts in succession resume their 120 places. At the same time the cam r lowers the catch q in order that the thrust member l may be able to return flush with the frame k for the purpose of throwing out the cap-like member d . Furthermore the cam v , 125 acting on the lever s , effects the return of the thrust member l directly, and that of the sleeve o through the medium of the shoulder l^2 .

The distributing valve u , Figs. 1 and 7, 130

then directs compressed air into the passage l' , and the cap like member d , having had its edge turned over the spring c , is thrown out of the machine.

5 The frame k may be mounted on a carriage k' which will carry it in a direction perpendicular to its axis, Fig. 1. In the present embodiment the sliding carriage k' is operated by the cam 6 to bring the 10 frame k opposite the positioning device. The arrangement of the frame k on a movable carriage facilitates the insertion of the cap-like member d in said frame.

The retaining springs c capable of being 15 engaged and fixed into cap like members in the manner hereinbefore described are of the kind comprising two resilient branches adapted to return to their initial positions after they have been moved apart.

20 The forms, details, accessories, materials and dimensions of this machine may of course be varied without thereby changing in any way the principle of the invention as set forth in the appended claims.

25 What we claim and desire to secure by Letters Patent of the United States is—

1. A machine for inserting the retaining springs in the cap like member of press buttons and turning the edges of the cap like member over the springs, comprising in combination:—a positioning tool for inserting the retaining spring into the cap like member of the press button; a tool for turning the edge of the cap like member 30 over the retaining spring; a sleeve for disengaging the retaining spring from the positioning tool and passing it into the cap like member of the press button; a thrust member receiving the cap like member of the 35 press button; an air-distributing valve for holding the cap like member of the press button in the thrust member by means of a vacuum and of subsequently expelling the said cap like member by injecting air; and means for actuating the parts of the 40 machine.

45 2. A machine for inserting the retaining springs in the cap like member of press buttons and turning the edges of the cap like

50 member over the springs, comprising in combination:—a positioning tool for inserting the retaining spring into the cap like member of the press button, consisting of a spring pressed blade provided with a projecting stop, and a slightly narrowed part 55 having a notch, the said blade receiving the retaining spring to be inserted; a tool for turning the edge of the cap like member over the spring; a sleeve for disengaging the 60 retaining spring from the positioning tool and passing it into the cap like member of the press button; a thrust member receiving the cap like member of the press button; an air-distributing valve for holding the cap 65 like member of the press button in the thrust

member by means of a vacuum and of subsequently expelling the said cap like member by injecting air; and means for actuating the parts of the machine.

3. A machine for inserting the retaining 70 springs in the cap like member of press buttons and turning the edges of the cap like member over the springs, comprising in combination:—a positioning tool for inserting the retaining spring into the cap like member of the press button; a tool for turning the edge of the cap like member over the spring, provided with a groove for the purpose of pushing the branches of the spring into the cap like member and of turning the 80 edge of the latter over the spring; a sleeve for disengaging the retaining spring from the positioning tool and of passing it into the cap like member of the press button; a thrust member receiving the cap like member of the press button; an air-distributing valve for holding the cap like member of the press button by means of a vacuum and of subsequently expelling the said cap like member by injecting air; and means for actuating the parts of the machine.

4. A machine for inserting the retaining 90 springs in the cap like member of press buttons and turning the edges of the cap like member over the springs, comprising in combination:—a positioning tool for inserting the retaining spring in the cap like member of the press button; a tool for turning the edge of the cap like member over the 95 spring; a sleeve for disengaging the retaining spring from the positioning tool and passing it into the cap like member of the press button, the said sleeve being provided internally with a stop for the positioning tool and externally with a controlling spring; a thrust member receiving the cap like member of the press button; an air-distributing valve for holding the cap like member of the press button in the thrust 100 member by means of a vacuum and of subsequently expelling the said cap like member by injecting air; and means for actuating the parts of the machine.

5. A machine for inserting the retaining 110 springs in the cap like member of press buttons and turning the edges of the cap like member over the springs, comprising in combination:—a positioning tool for inserting the retaining spring into the cap like member of the press button; a tool for turning the edge of the cap like member over the spring; a pusher for disengaging the retaining spring from the positioning tool and passing it into the cap like member of the press button; a thrust member receiving the cap like member of the press button, the said thrust member being pierced by a passage 120 through which air is drawn out or injected for the purpose of holding fast or throwing 130

out the cap like member of the press button; an air device for holding the hollow member of the button in the thrust member by means of a vacuum and for subsequently 5 expelling the said cap like member by injecting air; and means for actuating the parts of the machine.

6. A machine for inserting the retaining springs in the cap like member of press buttons and turning the edges of the cap like member over the springs, comprising in combination:—a positioning tool for inserting the retaining spring into the cap like member of the press button; a tool for turning 10 the edge of the cap like member over the spring; a sleeve for disengaging the retaining spring from the positioning tool and passing it into the cap like member of the press button; a thrust member receiving the 15 cap member of the press button; an air distributing valve for holding the cap like member of the press button in the thrust member by means of a vacuum while the retaining spring is being put into its place and 20 for subsequently expelling the said cap like member by injecting air after the flange of the said cap like member has been turned over the spring, the said distributing valve comprising a cylinder, a slide-valve piston, 25 air inlets adapted to be connected with a vacuum pipe and a pressure pipe respectively, and an opening in the slide-valve piston; and means for actuating the parts of the 30 machine.

35. 7. A machine for inserting the retaining springs in the cap like member of press buttons and turning the edges of the cap like

member over the springs, comprising in combination:—a positioning tool for inserting the retaining spring into the cap like member of the press button and a slide carrying said tool; a tool for turning the edge of the cap like member over the spring; a sleeve for disengaging the retaining spring from the positioning tool and passing it into the 40 cap like member of the press button; a thrust member receiving the cap like member of the press button and a slide carrying said thrust member; an air-distributing piston valve for holding the cap like member 45 of the press button in the thrust member by means of a vacuum and for subsequently expelling the said cap like member by injecting air; and means for actuating the parts of the machine, comprising a pulley, a shaft provided with a cam acting on the slide carrying the positioning tool, bevel pinions driving another shaft provided with a cam acting 50 on the slide carrying the thrust member, a valve cam operating the air-distributing 55 slide-valve piston, bevel pinions driving a shaft carrying cams for controlling the movements of the thrust member, and a lever for returning the thrust member to normal position, the whole as described and 60 illustrated.

In testimony whereof we affix our signatures in presence of two witnesses.
